PORTABLE VISE

John A. Waller, Beverly Hills, Calif.

Application September 3, 1938, Serial No. 228,359

3 Claims. (Cl. 81—41)

This invention relates to portable vise structures, and pertains particularly to a portable vise adapted for attachment to a bench, sawhorse, or other object.

5 One of the particular objects of the invention is to provide a portable vise device which may be secured to substantially any desired object, and which is subject to angular adjustment in position with respect to the support object so 10 as to adapt the same to use under substantially any circumstances.

A further object of the invention is to provide a device adapted for adjustment at different levels with respect to the object to which it is secured, 15 wherefore the device may be used in an upstanding position to secure the article to be worked on, or disposed in a lowered position at a level closely adjacent that of the support object.

A further object of the invention is to provide 20 a portable bench device which may be constructed of inexpensive materials, and which is adapted to occupy a minimum space when in folded condition, wherefore it may be transported from place to place with minimum difficulty.

25 The device of the present invention comprises, essentially, a base member having a clamp portion adapted for attachment to a support member, such as a bench, ladder-leg, or the like; a sub-base member rotatably mounted on said base member 30 and provided with locking means for fixing the sub-base member in any desired angular position with respect to the base member itself, the sub-base member being provided with a fixed jaw member. The device further comprises a second 35 jaw member slidably mounted with respect to the sub-base portion and adapted for movement toward and away from the first jaw member, and screw means for moving the second jaw member. The device preferably also includes a construction 40 which provides for sliding movement of the sub-base member with respect to the base member, which means may be associated with the means for establishing the sub-base member at any desired rotative position with respect to the base 45 member, whereby the jaw portion of the device may be established at a particular level with respect to the working surface to which the clamp or vise member is attached.

50 Other objects of the invention will be apparent from the following description of a preferred embodiment thereof, or will be specifically brought out therein. Certain drawings are employed to illustrate the invention and referring thereto:

55 Fig. 1 is a perspective view of the device, show-

ing the same in position on a bench or other ledge, ready for use;

Fig. 2 is a side elevation thereof showing in full and dot-dash lines alternative positions of the vise member with respect to the support 5 means;

Fig. 3 is an end elevation thereof, taken on line 3—3 in Fig. 2;

Fig. 4 is a rearward view of the device taken substantially along line 4—4 in Fig. 3;

Fig. 5 is a corresponding view of the device taken in the opposite direction, on line 5—5 in Fig. 3;

Fig. 6 is a partly broken-away rear elevation of the device taken on line 6—6 in Fig. 3;

Fig. 7 is a view corresponding generally to that shown in Fig. 2, showing a device mounted on an inclined support member, with the vise itself disposed horizontally in position for use; and

Fig. 8 is a detail of the device taken on line 20 8—8 in Fig. 3.

Referring more particularly to the drawings, I have illustrated the device as comprising a base member 1 having a flat plate portion 2 provided with a lip portion 9 which may extend substantially at right angles to the plate portion 2, as shown more particularly in Fig. 3, and a clamp screw 3 provided with a wing nut 4 and secured to the plate portion 2 of the base member through a side arm connection 5 and adapted for threaded movement toward and away from the lip 9, wherefore a support structure may be engaged as at 6 between said lip member 9 and the bearing portion 7 of the screw 3. In this connection, it is usually convenient to recess the support structure 6 in some such manner as shown at 8, in order to receive the lip 9, as shown in Fig. 3. A sub-base member 11, carrying a fixed vise jaw 12, is rotatably disposed upon the plate portion 2 of the base member 1, as through the agency of a bolt 13 mounted in a slot 14 in the portion 2 and extending through a bore 15 in the sub-base 11, and provided with a locking wing nut 16. In order to assist in positioning the sub-base 11 at a desired angular position with respect to the base 1, I provide a plurality of lugs 11a disposed radially with respect to the bore 15 at the rearward face of the sub-base 11, adapted to engage with a pair of longitudinal lugs 1a formed in the forward face of the plate portion 2 at opposite sides of the slot 14. It will be understood that when the lock nut 16 is released, allowing the sub-base to be slidably moved upwardly or downwardly with respect to the base 1, a given rotative adjustment of the sub-base 11 with respect 45

50 to the base 1, I provide a plurality of lugs 11a disposed radially with respect to the bore 15 at the rearward face of the sub-base 11, adapted to engage with a pair of longitudinal lugs 1a formed in the forward face of the plate portion 2 at opposite sides of the slot 14. It will be understood that when the lock nut 16 is released, allowing the sub-base to be slidably moved upwardly or downwardly with respect to the base 1, a given rotative adjustment of the sub-base 11 with respect 55

to the base 1 will be preserved by the continued engagement of the lugs 11a with the lugs 1a, and if a new rotative position of the sub-base 11 with respect to the base 1 is desired, it is merely necessary to back off the lock nut 16 to such an extent that the sub-base 11 can be pulled away from the base 1 so as to free the lugs 11a and 1a, the sub-base moved to a new rotative position, and the wing nut tightened again. Due to the longitudinal extension of the lugs 1a, the same rotative position of the sub-base 11 may be preserved at all positions thereof with respect to the base 1, within the limits of movement defined by the slot 14.

15 The sub-base 11 is provided with a laterally extending support arm 21, which serves as a slide for a second jaw member 22, and said support arm carrying an overhanging bearing 23 which supports a screw 24 on which the jaw 22 is threadedly disposed as at a boss 25. The extreme end of the screw 24 is provided with a hub 26, through which an operating lever 27 may be extended.

20 The jaw 22 is preferably also provided with a support arm 28, extending parallel with the support arm 21, and passing below the jaw 12 and above the hub portion 29 of the sub-base 11 which surrounds the bolt 13. A positioning screw may be provided as at 31, adapted to engage a lateral edge of the member 28 as at 32, to assist 30 in maintaining the member 28 in relative alignment with respect to the sub-base 11.

25 As will be seen from a consideration of Fig. 2, the vise member may be so disposed with respect to a support 6 as to cause the jaws 12 and 22 to be disposed significantly above the upper edge of the support 6, as shown in full lines in Fig. 2. The device may be lowered as shown in dot-dash lines at A so that the upper edges of the jaws 12 and 22 lie substantially flush with 40 the upper edge or face of the lip 9, and thus flush with the upper edge of the support 6 if the lip 9 is disposed within a chipped-out recess 8 as shown in Figs. 1 and 3. In either the elevated or depressed positions as shown in full lines and 45 at A respectively, the device may be inclined at an angle to the support, as shown in dot-dash lines at B in Fig. 2. This arrangement of the device makes it highly advantageous from the standpoint of facilitating work on small pieces, 50 such as is often encountered in cabinet work, in that the device may be inclined at an angle to the work bench and a surface planed or sawed at a desired angle while permitting the user to adopt the most comfortable position for his particular working requirements.

55 In addition to the features which result when the device is clamped directly upon a flat working surface such as a bench or the like shown at 6, the relative adjustment features of the present 60 invention make it particularly useful where it is required that the device be clamped upon a ladder-leg, sawhorse leg, or the like. Such a situation is illustrated in Fig. 7, in which an inclined support member is indicated at 35, such as may 65 result from the use of a sawhorse leg or the like as a support. Where the base 1 is attached to such an inclined support, it will frequently be desirable to clamp the same directly to the support, using the inner face 2a of the lip 9 for engagement of one side of the support, instead of recessing the support as shown at 3 in Figs. 1 and 3. With this arrangement the jaws 22 and 12 may be disposed in a substantially vertical position, irrespective of the particular angle of 70 disposition of the support 35, wherefore the de-

vice may be used to support the edge of a door or the like which a carpenter may be required to plane, allowing the door itself to rest on the floor or other working surface and the vise member relied upon to maintain the door in its desired vertical position. 5

I preferably also provide the device with a tongue member 36 extending rearwardly from the fixed jaw 12, as shown more particularly in Figs. 1, 3, 4, and 7, so that relatively heavy pieces 10 of lumber may be butted against the device and held in position during planing or draw-knife operations, for example. Other modifications of the device will be apparent to those skilled in the art, for which reason I do not choose to be limited to the herein delineated and described 15 modifications, but rather to the scope of the subjoined claims.

From the above description, it will be apparent that the device is adapted for attachment to 20 any structure small enough to be clamped between the lip 9 and the bearing portion 7 of the screw 3. These bearing portions are defined as opposing upper and lower shoulder means in the subjoined claims, primarily for the sake of simplicity of description, inasmuch as in use on a bench these shoulder means will be in an upper and lower relation, as shown in the drawings. Where the vise is clamped to a vertical support, after the general manner shown in Fig. 7, the 25 "upper" and "lower" significance is lost but the general terminology is still applicable. It will be appreciated that the fixed and movable jaws 12 and 22 will be provided with opposed work-engaging faces disposed in parallel planes, as is 30 customary in ordinary vise constructions, and the relative movement of the jaws in use will be normal to such planes. The pivot pin or bolt 13 is disposed below the position of the upper shoulder 9 (in normal use when clamped to a 35 flat bench member) and the axis of rotation of the sub-base 11 as defined by the bolt 13 will be parallel to the aforesaid planes, wherefore the device is capable of withstanding the forces set up at the jaws 12 and 22 and communicating 40 such forces to the clamping means with minimum distortion of the base and sub-base. 45

I claim:

1. A portable vise which comprises: a base member provided with a clamp portion for attachment to a support, and having an elongated slot in one side thereof; bolt means extending through said slot; a sub-base member provided with a hub portion disposed over said bolt means and carrying a vise assembly; a plurality of 50 spaced lugs disposed radially about one side of said hub member and directed toward said base member; a longitudinally extending lug on said base member extending along each side of said elongated slot and adapted to engage between 55 said spaced lugs on said sub-base member; and means for clamping said sub-base member to said base member to cause the respective lug means on said base member and sub-base member to be in positive engagement. 60

2. A portable vise which comprises: a sub-base provided with a fixed jaw member having a work-engaging face extending in a plane; a movable jaw member having a work-engaging face and disposed in a plane substantially parallel to 70 said first-named plane and slidably movable toward and away from said fixed jaw member in a direction substantially normal to said planes; a main base member provided with opposing upper and lower clamping shoulders at one side 75

thereof for attachment of the vise to a support; a bolt member mounted on said main base member and extending rotatably through said sub-base to define a pivotal mount for said sub-base 5 on said main base member at the other side of said main base member, and defining an axis of rotation extending substantially parallel to said planes and substantially normal to said direction of movement of said movable jaw member, and 10 said bolt member extending through an upwardly and downwardly extending slot provided in said base member and adapted for upward and downward sliding movement therein; upwardly and downwardly elongated lug means on 15 said main base member extending outwardly therefrom at said other side thereof, adjacent and substantially parallel to said slot; cooperating lug means on said sub-base positioned to engage said first-named lug means at various 20 rotative positions of said sub-base with respect to said main base member; and clamp means cooperating with said bolt member to fix the rotative position of said sub-base with respect to said main base member and to fix the position 25 of said bolt member within said slot.

3. A portable vise which comprises: a base member provided with a clamp portion for attachment to a support; a sub-base member slidably mounted on said base member for pivotal

movement about an axis extending transverse to the direction of slidable movement thereof; locking means cooperating with said base member and said sub-base member and operable to constrain said sub-base member with respect to 5 said base member; a pair of cooperating jaw members mounted on said sub-base member for relative sliding movement toward and away from one another in a direction transverse to said axis, and cooperating lug means on said base member 10 and said sub-base member, said cooperating lug means comprising lug means on said base member extending in the direction of slidable movement of said sub-base member, and lug means on said sub-base member arranged radially about 15 the axis of pivotal movement thereof, said cooperating lug means being adapted to interengage one another to positively fix said base members in any one of a plurality of established rotative positions in cooperation with said locking 20 means when said locking means is tightly locked, and being of such length in the direction of said axis as to be further adapted to interengage and constrain said base members substantially in such an established rotative position when said 25 locking means is loosened to facilitate sliding movement of said sub-base member with respect to said base member.

JOHN A. WALLER.
